DOUBLE OPERATION FORMING DIE

Leon Hardman, Wantagh, N. Y.

Application June 7, 1954, Serial No. 434,763

1 Claim. (Cl. 153—21)

This invention relates to metal forming dies and more particularly to such dies adapted to perform double operations on sheet metal, for forming both Acme type and Pittsburgh type sheet metal locks.

In the sheet metal industry, for instance in connection with ducts, for air conditioning and heating purposes, large sheets of metal must be formed to fabricate the ducts. Since these ducts are often large, they are generally formed in portions that can be packed flat for easy warehousing and transportation. The ducts are then assembled in the field at the point of installation by locking the side portions with prefabricated locking portions. The present invention provides means for forming these locking pieces.

One of the problems in this industry is due to the fact that long sections, for instance, 8 to 10 feet long, are prefabricated. Therefore, the forming dies must be equally as long, 8, 12 or more feet. These dies being so large require tremendously heavy presses.

Many of the duct members, especially the locking means require two or more operations to perform them properly. For instance, in the locking member, there is generally a first forming and then a squeezing operation. These operations could be formed in a conventional manner on separate dies. However, this would require separate handling and separate set-ups and would tie up two presses, which are very large and very expensive machines, as well as requiring handling and storage between operations.

Handling and storage are very serious problems due to the size of the pieces involved. For instance, to handle a piece of sheet metal six feet long takes at least two men. The present invention provides a die which performs two operations on the same press and die, thereby eliminating the need for a second set-up or press and eliminating all handling and storage between operations.

In one embodiment of the present invention the die has two portions, a front and an aft portion. The sheet metal is inserted from the front and under the aft portion and the first operation is performed by the aft portion, which for instance, is a forming operation. The metal is then withdrawn towards the front and a second operation, for instance a closing or hammering operation is performed on the next stroke of the press. The die is designed so that the front portion of the press does not interfere with the metal during the first operation performed by the aft portion.

The dies of the present invention are capable of forming both Pittsburgh and Acme type locks for sheet metal. These are well known locks in the sheet metal industry.

Accordingly, a principal object of the invention is to provide new and improved double operation forming die means.

Another object of the invention is to provide new and improved means for performing two operations on sheet metal with the same die.

Another object of the invention is to provide new and improved metal forming die means which are simple and

economical in operation and which eliminate separate set-ups and storage and handling problems between operations.

Another object of the present invention is to provide new and improved die means for forming both Pittsburgh and Acme type locks in sheet metal.

These and other objects of the invention will be apparent from the following description of drawings of which:

10 Figure 1 is an elevation sectional view of an embodiment of the invention illustrating first and second operations on a Pittsburgh type lock. Figures 1A and 1B show a Pittsburgh lock.

Figure 2 is an elevation sectional view of another embodiment illustrating a second type locking operation forming an Acme type lock.

Figures 3 and 3A are elevation sectional views illustrating an Acme type lock.

Figure 4 is an elevation view of another embodiment of the invention utilizing a spring loaded portion.

Referring to Figure 1, there is shown a die comprising lower die member 1, and upper die member 2. The upper die member is adapted to move vertically with respect to the lower die member in a press, which is not shown. The front of the die is to the right. This particular embodiment of the invention is designed to perform two operations. The first is a forming operation and the second is a closing operation which squeezes the formed portion so that the metal describes a 180° loop which nests in an offset. The sheet to be locked is inserted inside the 180° bend and will be in the same plane as the first sheet, to form a Pittsburgh type corner lock as shown at D, Figure 1B.

The aft portion of the lower die comprises a positive member 3, which is adapted to be inserted in a recess 4, in the upper member. Just to the left of the positive member 3 of the lower die member 1 is a V shaped depression. The upper die member has a V projection 5' which is adapted to be inserted in the lower portion 5.

40 The right or front portions of the die are designed so as not to interfere with the sheet which the first operation is being performed. Therefore, the sheet may extend out the front of the die any distance.

The operation of the die is as follows:

45 A flat sheet of metal is inserted from the front or right hand side to the rear of the die, against a suitable stop 15 incorporated in the die.

The die is then squeezed together and forms the metal piece A in the form as shown in Figure 1. When the die is opened the metal piece A is retracted to the position B. On the next stroke of the press the formed or crimped metal sheet B will be squeezed flat between the upper and lower die faces. A spacer 13 is attached to the lower die face to provide a space 13', Figure 1A, in the finished product C. The spacer permits easier insertion of the sheet metal 16 which is to be locked to the piece D the locking portion. The end 17 is then hammered over when being installed to form the corner lock, as shown in Figure 1B.

60 In using the present die the metal sheet may be inserted by one man from the front for the first operation then retracted slightly for the second operation and then removed thereby eliminating all handling and storage between operations. Therefore, the embodiment of Figure 1 shows means for forming a Pittsburgh type sheet metal lock with one die performing two separate operations in a minimum of time and with a minimum of handling.

A, B and C show the successive forms taken by the metal blank and the form D shows the piece 16 of the member to be locked inserted in the Pittsburgh lock D. This insertion is generally performed in the field on the

job and then the left hand edge 17 of the lock is then hammered over.

Figure 2 shows another embodiment of the invention which is adapted to form the Pittsburgh type lock in exactly the same fashion as described in connection with Figure 1 and which also may be used to form an Acme type lock. In this modification, the die face slopes downwardly at a slight angle towards the front or right hand side. The members A', B', C' and D' illustrate the formation of the Acme type lock. In forming the Acme type lock, a stop, which is the pin 20, is inserted in a hole 21 in the lower die 1. A hole 22 adapted to receive pin 20 must be inserted in the upper die 2. This pin 20 will be removed, of course, when it is designed to form a Pittsburgh type lock.

The operation of forming the Acme type lock is as follows:

A flat metal blank A' is rested on the lower die in a substantially horizontal position and held against the stop 20. The first stroke of the press will form the piece B' which is then retracted by the operator and then held in the position C', in notch 19. The next stroke of the press will turn over and squeeze the hook of the member C' to form the complete locking member D'.

Figures 3a and 3b show the formation of a complete Acme lock in the field. The two pieces D' are hooked together as shown in Figure 3a and then hammered flat as shown in Figure 3b.

Figure 4 shows another embodiment of the invention utilizing a spring loaded projecting member 30 in the upper die 32. The lower die 31 is substantially the same as shown in Figure 2 except it slopes down to the front. One of the primary problems in these dies is that the first contact with the metal blank should be made at the point 33 and not at the point 34. When the first contact is made at point 34 the metal blank is liable to be twisted and turned in the operator's hands. The embodiment of Figure 4 is specifically designed so that the first contact will be made at the point 33 and in addition due to the

spring loading of the member 30 by the spring 40, this impact will be automatically compensated so that it will not be so great as to shift the position of the metal piece which is being formed. Otherwise the operation of the embodiment of Figure 4 is the same as that of Figures 1 and 2.

I claim:

A double operation sheet metal die for performing successive forming and squeezing operations on the same portion of a metal sheet comprising an integral lower member having a first V-shaped recessed portion in the top plane thereof spaced from a first side of said lower member, a second recessed portion spaced from said first recessed portion, said second recessed portion comprising first and second step portions from said top plane, a spacer mounted on said first step portion and extending over said second step portion, a first stop affixed to said first side of said lower member, an upper member having a first V-shaped projecting member positioned to mate with said first recessed portion of said lower member, said upper member having a second projecting member positioned to mate with said spacer, said V-shaped means being arranged to form a V-bend in a metal sheet during a first mating of said dies and said spacer cooperating with said second step portion of said lower member and said second projecting portion of said upper member to form said V-bend into a U shape of predetermined spacing around said spacer during a second mating of said dies.
